[57] CLAIM

The ornamental design for wall attachable bifurcated hook, as shown and described.

DESCRIPTION

FIG. 1 is a front, top and right side isometric view of a wall attachable, bifurcated hook showing my new design;

FIG. 2 is a front elevational view thereof;

FIGS. 3 and 4 are respectively left and right side elevational views thereof;

FIGS. 5 and 6 are respectively top and bottom plans views thereof; and

FIG. 7 is a rear elevational view thereof.

Fig. 1.
